UNITED STATES PATENT OFFICE.

WALTER H. WHITTIER, OF GRAND RAPIDS, MICHIGAN, ASSIGNOR TO GRAND RAPIDS REFRIGERATOR COMPANY, OF GRAND RAPIDS, MICHIGAN, A CORPORATION OF MICHIGAN.

REFRIGERATOR-LINING.

984,873.

Specification of Letters Patent. Patented Feb. 21, 1911.

Application filed August 6, 1910. Serial No. 575,904.

To all whom it may concern:

Be it known that I, WALTER H. WHITTIER, a citizen of the United States of America, residing at Grand Rapids, in the county of Kent and State of Michigan, have invented certain new and useful Improvements in Refrigerator-Linings; and I do hereby declare the following to be a full, clear, and exact description of the invention, such as will enable others skilled in the art to which it appertains to make and use the same.

My invention relates to improvements in metal linings for refrigerators, and its object is to provide a lining that is germ proof, sanitary and easily cleaned, and to provide the same with various new and useful features hereinafter more fully described and particularly pointed out in the claims, reference being had to the accompanying drawings in which:

Figure 1 is a perspective of a refrigerator lining ready to be placed in the refrigerator. Fig. 2 is a plan of a sheet metal blank for forming such lining shown on a reduced scale. Fig. 3 is a vertical section of the device shown in Fig. 1 taken on the line 3—3 of Fig. 4. Fig. 4 is a horizontal section showing the bottom in plan view, and—Fig. 5 is a perspective detail of one of the lower corners of the lining before the corner is finally closed and rounded.

Like numbers refer to like parts in all of the figures.

The vertical walls and the bottom of my improved lining are formed of a single piece of sheet metal first cut in accordance with the plan shown in Fig. 2 in which the middle portion 1 forms the back wall, 2 are side portions to form the sides of a finished lining. The middle triangular portion 3 extending from the back portion forms the rear portion of the bottom, and the parts 4 extending from the side portions 2 form the side portions of the bottom. The outer edges of the side portions 2 and bottom portions 4 are extended as at 8 to form the side flanges and as at 6 to form the depending front flange, and to properly round the corners of the lining where the corners of the side and back join the corners of the bottom triangular recesses 5 are cut between the middle bottom part 3 and the side bottom parts 4 to remove surplus material, and the adjacent margins pressed inward forming a portion of a globe at this point and re-

cesses are also formed which sever and space apart the extensions 6 and 8 at the outer margins of the blank, the inner ends of these recesses being convex in a one-fourth circle form as shown at 7. This blank can be made from a rectangular piece of sheet metal by cutting recesses in the margin of the same at one end as shown which is then bent or folded in proper form to form the back, sides and bottom, and the side and bottom flanges of the finished structure, the vertical and horizontal angles of the same being rounded or concaved in one-fourth circle form, and the edges of the parts 3 and 4 brought together as indicated in the drawings. A top sheet 9 is also provided having a downwardly turned flange 10 at the front and with rounded corners to fit within the top of the described structure. When thus formed the recesses 5 will form openings as at 5 in Fig. 5 which by a suitable tool can easily be closed by bending the metal inward around the same and thus forming a smoothly rounded corner as at 5^a.

The seams between the parts 3 and 4, and between the top 9 and vertical walls can be soldered, welded or brazed to insure a satisfactory, tight and germ proof structure. I prefer welding the same, which can be readily done by means of a suitable blow pipe or an electric welder.

This lining has very few seams, and all the corners except at the top are concave on the inner side whereby no sharp angles exist to afford lodgment for anything whatever, thus furnishing a lining which is very easily kept clean.

By welding this structure by means of the blow pipe as suggested, it will stand the heat necessary to coat the same with enamel throughout which I prefer to do thus making a very durable and satisfactory refrigerator lining.

I am aware that sheet metal has been used for making linings for refrigerators and also that earthenware linings with concave or rounded angles have been used. I am, however, not aware of any prior method of forming sheet metal linings as herein described, or of any sheet metal lining having the rounded or concave angles as shown herein.

What I claim is:—

1. A refrigerator lining, comprising integral vertical walls, and an integral bot-

tom, said lining having concave or rounded corners, the bottom being formed of a triangular portion extending from the rear wall together with side pieces extending 5 from the side walls joined to the triangular piece and to each other.

2. A refrigerator lining, comprising side walls and a rear wall together with vertical front flanges to the side wall, formed up 10 with rounded vertical corners, a bottom integral with said walls and formed of integral members extending inward from the rear wall and side walls and joined at the edges to each other, the side members there- 15 of also having a downwardly extended front flange, and a top member secured to the rear and side walls and also having a depending front flange.

3. A refrigerator lining, comprising two 20 vertical walls, and a bottom integral therewith the walls being rounded where joined to each other and to the bottom, and the metal formed inward where the corners of the walls and the corner of the bottom meet 25 to form a rounded or partially globular portion to the lining.

4. A blank for forming a sheet metal refrigerator lining, comprising a series of 30 rectangular portions to form the vertical walls, bottom portions extending from the respective ends of the first named portions and adapted to form a continuous bottom when folded inward at right angles to the

side portions, side extensions on the blank to form flanges and recesses in the sides di- 35 viding the side extensions.

5. An integral sheet metal blank for a refrigerator lining, comprising three rectangular portions to form the rear and side walls, a triangular extension on the middle 40 portion to form the rear portion of the bottom, extensions on the side portions to form the side portions of the bottom, side extensions to form flanges, said blank also having triangular recesses between the bottom portions to permit forming rounded bottom corners and side recesses in the flange extensions having rounded inner ends to form rounded corners in the finished structure. 45

6. A refrigerator lining, comprising rear 50 and side walls and front vertical flanges, said lining having four rounded or concave vertical corners, a bottom formed of three portions integrally and inwardly projecting from the respective rear and side walls and 55 joined to each other by welding, said lining also having rounded bottom corners and a depending front flange, and a top welded at the adjacent edges to the rear and side walls. 60

In testimony whereof I affix my signature in presence of two witnesses.

WALTER H. WHITTIER.
